CLAIM

I claim the ornamental design for a beverage container insert, as shown and described.

DESCRIPTION

FIG. 1 is a top, front perspective view of a beverage container insert showing my new design;

FIG. 2 is a bottom, rear perspective view of the beverage container insert of FIG. 1;

FIG. 3 is a left side view of the beverage container insert of FIG. 1;

FIG. 4 is a right side view of the beverage container insert of FIG. 1;

FIG. 5 is a rear view of the beverage container insert of FIG. 1;

FIG. 6 is a front view of the beverage container insert of FIG. 1;

FIG. 7 is a top plan view of the beverage container insert of FIG. 1; and,

FIG. 8 is a bottom plan view of the beverage container insert of FIG. 1.

The broken lines consisting of dashes show an environment that forms no part of the claimed design. The broken lines consisting of a double-dot/dash pattern show a boundary of the claimed design. The stippled shading in the drawings indicate a surface contrast between adjacent surfaces.
